PLASTIC HANDLE

Gerald T. Tracy, 3217 W. 47th Place, Chicago, Ill.

Filed Sept. 20, 1963, Ser. No. 76,657

Term of patent 14 years

(Cl. D58—26)

Fig. 7

Fig. 8

Fig. 9

Fig. 10

Fig. 12

Fig. 11

FIG. 1 is a top plan view of a plastic handle showing my new design;

FIG. 2 is a side view taken from the left hand side of FIG. 1;

FIG. 3 is an end view taken from the bottom end of FIG. 1;

FIG. 4 is an enlarged cross sectional view taken along line 4—4 of FIG. 1 and looking in the direction of the arrows;

FIG. 5 is an enlarged cross sectional view taken along line 5—5 of FIG. 1 and looking in the direction of the arrows;

FIG. 6 is a perspective view thereof on a reduced scale;

FIG. 7 is a top plan view of another embodiment of a plastic handle, showing my new design;

FIG. 8 is a side elevational view thereof taken from the left of FIG. 7;

FIG. 9 is an end elevational view thereof taken from the bottom end of FIG. 7;

FIG. 10 is an enlarged cross-sectional view thereof taken along line 10—10 of FIG. 7;

FIG. 11 is an enlarged cross-sectional view thereof taken along line 11—11 of FIG. 7; and

FIG. 12 is a perspective view thereof on a reduced scale. The cans shown in dot-dash lines in FIGS. 6 and 12 are for illustrative purposes only.

I claim:

The ornamental design for a plastic handle, substantially as shown and described.
